(57) CLAIM

The ornamental design for a removable handle, as shown and described.

DESCRIPTION

FIG. 1 is a right perspective view of a removable handle showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a left perspective view thereof in its environment.

The broken lines in the figures are included for the purpose of illustrating visible environmental structure and form no part of the claimed design.

1 Claim, 5 Drawing Sheets

FIG. 1

FIG. 2FIG. 3

FIG. 4

FIG. 5

FIG. 6

FIG. 7

FIG. 8
